(57) **CLAIM**

The ornamental design for multi-cross with bars, as shown and described.

DESCRIPTION

FIG. 1 shows a front view of the invention.

FIG. 2 shows a back view of the invention.

FIG. 3 shows a top view of the invention.

FIG. 4 shows a bottom view of the invention.

FIG. 5 shows a side view of the invention.

FIG. 6 shows a side view of the invention.

FIG. 7 shows an unassembled front view of parts of the invention.

FIG. 8 shows an unassembled side view of the invention.

FIG. 9 shows an unassembled side view of a coupling member of the invention.

FIG. 10 shows an unassembled front view of a coupling member of the invention; and,

FIG. 11 shows an unassembled top view of a coupling member of the invention.
